UNITED STATES PATENT OFFICE.

LUKE KAVANAUGH, OF WATERFORD, NEW YORK.

DESIGN FOR A KNITTING-BURR BLADE.

SPECIFICATION forming part of Design No. 15,587, dated December 2, 1884.

Application filed September 10, 1884. Term of patent 14 years.

To all whom it may concern:

Be it known that I, LUKE KAVANAUGH, a citizen of the United States, residing in the town of Waterford, in the county of Saratoga and State of New York, have invented and produced a new, useful, and original Shape, Configuration, or Design for Knitting-Burr Blades, of which the following is a specification, reference being had to the accompanying drawing, which represents in side elevation a knitting-burr blade embodying the design.

The distinguishing feature of this design is the outline shape of the edges of the blade. The blade has a flaring shank bordered by the edges *a b*, *b c*, and *c d*, and has the main portion, bounded by the upper edge, *a e*, curved convexly in its lengthwise direction throughout its whole extent, the lower edge, *f e*, inclined at an acute angle to the edge *a e*, and meeting the latter in the rounded corner *e*, and the straight edge *d f* inclined at an acute angle to the edge *a e* and at an obtuse angle to the edge *e f*, and forming, with the latter, the plainly-obtuse angle *f*, and all shaped so that 25 a line *f g* drawn perpendicular to the edge

df from the angle *f* crosses the body of the blade and its edge *a e* at a considerable distance from the edge *ef* and corner *e*, as illustrated in the accompanying drawing.

I claim as new—

The design for a knitting-burr blade herein shown and described, the same consisting of the flaring shank bordered by the edges *a b*, *b c*, and *c d*, and the main portion, bordered by the edge *a e*, curved convexly throughout its 35 whole extent, the edge *f e* inclined at an acute angle to the edge *a e*, and meeting the latter in the rounded corner *e*, and the straight edge *d f* inclined at an acute angle to the edge *a e* and at an obtuse angle to the edge *e f*, and 40 forming, with the latter, the plainly-obtuse angle *f*, as set forth.

In testimony whereof I hereunto set my hand, in the presence of two subscribing witnesses, this 8th day of September, 1884.

LUKE KAVANAUGH.
